UNITED STATES PATENT OFFICE.

THOMAS BERRY AND WILLIAM BREYMAIER, OF BUCYRUS, OHIO.

CEMENT BURIAL-VAULT.

1,154,085.

Specification of Letters Patent. Patented Sept. 21, 1915.

Application filed December 10, 1913. Serial No. 805,825.

To all whom it may concern:

Be it known that we, THOMAS BERRY and WILLIAM BREYMAIER, citizens of the United States, residing at Bucyrus, in the county of Crawford and State of Ohio, have invented a new and useful Cement Burial-Vault, of which the following is a specification.

The device forming the subject matter of this application is a burial vault, the structure ordinarily being made of cement or concrete.

One object of the present invention is to provide novel means for effectively sealing the lid to the case, throughout the entire periphery of the lid and the case, thereby to prevent an escape of the products of decomposition.

Another object of the invention is to provide a burial case of the type above described having a false bottom of novel form, it being possible to seal the false bottom to the case in the manner described in connection with the case and the lid.

Another object of the invention is to provide a burial case or vault in which the intermediate portion of the case may be removed readily, it being possible to set the lid directly on the false bottom and thereby produce a shallow receptacle for special purposes, the sealing elements of the lid and the case upon the one hand, and the case and the false bottom upon the other hand being so constructed that when the lid rests directly upon the false bottom, these elements may be sealed together effectively.

It is within the scope of the invention to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing: Figure 1 shows one form of the invention in top plan, a portion of the lid being broken away; Fig. 2 is a longitudinal section of the structure shown in Fig. 1; Fig. 3 is a cross section on the line 3—3 of Fig. 2; Fig. 4 is a

cross section showing a modified form of the invention.

In the form of the invention which is disclosed in Figs. 1, 2 and 3 there is provided a false bottom 1 having an upstanding peripheral flange 2 equipped with an internal shoulder 3. A case 4 rests upon the shoulder 3 and includes a bottom 25 having perforations 5, the bottom 25 of the case proper being spaced from the false bottom 1. The outer wall of the case 4 is spaced apart from the inner wall of the flange 2 to define a slot 6 which is open at the top. In the outer wall of the case 4 and in the inner wall of the flange 2 oppositely disposed grooves 7 are formed. When the parts are positioned as shown most clearly in Fig. 3, a sealing medium 8 may be poured into the slot 6 and this sealing medium will expand in the alined grooves 7 to form a locking and sealing rib 9. The grooves 7 extend entirely around the elements in which they are formed, and therefore the sealing rib 9 is continuous and unbroken around the entire periphery of the structure.

From the description as thus far proceeded with it will be understood that as the corpse decomposes, the liquid oozing from the corpse will pass through the perforations 5 in the bottom 25 and will lodge upon the false bottom 1.

The case 4 is equipped adjacent its upper end with a flange 10 having an internal shoulder 11 and upon the shoulder 11 rests a flange 12 constituting a part of a lid 14. The flange 10 and the flange 12 are spaced apart to define a slot 15, and grooves 16 are formed in the flanges, the grooves being oppositely disposed. The sealing medium is indicated at 17 and forms a rib 18 in the grooves 16 as before described. The shoulders 3 and 10 serve as closures, respectively, for the lower ends of the slots 6 and 15 and since the case 4 rests on the shoulder 3, and since the flange 12 of the lid 14 rests upon the shoulder 11, the sealing medium will be prevented from flowing laterally into the interior of the case.

From the foregoing it will be noted that it is necessary merely to set the case 4 on the shoulder 3 of the false bottom and pour the sealing medium 8 into place, the flange 12 of the lid 14 being placed on the shoulder 11 and the sealing medium 17 being poured into place, whereupon, owing to the presence of the sealing ribs 9 and 18, it will be im-

possible for the products of decomposition to leak out of the structure.

In Fig. 4 there is shown a case 19 having a flange 20 provided with a shoulder 21, the lid being indicated at 22 and having a flange 23, the sealing medium hereinbefore described being duplicated and being represented generally by the reference character 24. In substance, that form of the invention shown in Fig. 4 amounts to no more than omitting the perforations 5 from the case 4 and dispensing with the false bottom 1. At times, a shallow burial vault may be required, for instance when bones are to be re-interred, or when a corpse is so badly disintegrated or cut up that a formal burial is undesirable. Under such circumstances, the case 4, referring to Fig. 3, may be dispensed with entirely, the flange 12 of the lid 14 being permitted to rest directly on the shoulder 3 of the flange 2 of the false bottom 1. Under such circumstances, the groove 16 in the flange 12 will be lined up with the groove 7 in the flange 2, and the sealing operation may be carried out as before described, the vertical distance from the groove 16 in the flange 12 to the shoulder 11 being equal to the vertical distance from the groove 7 in the flange 2 to the shoulder 3.

It has been stated hereinbefore that the structure preferably is fashioned from concrete and, without specific illustration, it will be understood that reinforcements may be provided whenever and wherever necessary,

this detail conferring no novelty and being well within the scope of any skilled mechanician.

Having thus described the invention, what is claimed is:—

A mortuary receptacle comprising a false bottom having an upstanding flange provided with an internal shoulder; a case resting on the shoulder and spaced from the flange to define a slot, the case including a main bottom spaced from the fake bottom, the case having an upstanding flange provided with an internal shoulder; and a lid resting on the shoulder of the case and spaced from the flange of the case to define a slot, the flange of the false bottom and the case proper, and the flange of the case and the lid, having oppositely disposed grooves opening into the respective slots, the sets of grooves being spaced equally from the respective shoulders, and the case being removable, whereby when the lid rests upon the shoulder of the flange of the false bottom, the groove of the lid will be disposed opposite to the groove in the flange of the false bottom.

In testimony that we claim the foregoing as our own, we have hereto affixed our signatures in the presence of two witnesses.

THOMAS BERRY.

WILLIAM BREYMAIER.
